UNITED STATES PATENT OFFICE.

CLARENCE T. EVANS, OF MILWAUKEE, WISCONSIN, ASSIGNOR TO THE CUTLER-HAMMER MFG. CO., OF MILWAUKEE, WISCONSIN, A CORPORATION OF WISCONSIN.

OVERLOAD CIRCUIT-BREAKER.

1,271,875.

Specification of Letters Patent.

Patented July 9, 1918.

Application filed June 28, 1917. Serial No. 177,454.

To all whom it may concern:

Be it known that I, CLARENCE T. EVANS, a citizen of the United States, residing at Milwaukee, in the county of Milwaukee and 5 State of Wisconsin, have invented new and useful Improvements in Overload Circuit-Breakers, of which the following is a full, clear, concise, and exact description, reference being had to the accompanying drawing, forming a part of this specification.

This invention relates to overload circuit breakers and more particularly to those which are non-closable on overload.

Among the objects of the invention is to 15 provide a circuit breaker of the character stated having few and rugged parts compactly arranged for inclosed mounting and also arranged for quick and positive response to overloads.

20 A further object is to provide a circuit breaker of the aforesaid character adapted to insure a wide and substantially uniform separation of its contacts when tripped either manually or by overloads.

25 Other objects and advantages will herein-after appear.

In the accompanying drawing

Figure 1 is a front elevational view of an embodiment of the invention;

30 Fig. 2 is a vertical sectional view substantially on line $a-a$ of Fig. 1;

Fig. 3 is a similar view showing certain parts in altered relation; while,

35 Fig. 4 is a side elevational view showing details of the tripping mechanism.

Referring to the drawing, the same illustrates a double pole circuit breaker comprising a pair of fixed contacts 1 and 2 mounted side by side for engagement by a pair of 40 movable contacts 3, 4, the latter being carried in spaced relation upon a switch arm 5 which is pivoted at 6 upon a manually operable and lockable lever 7. A spring 8 fixed between said arm 5 and a part of said 45 lever serves to bias the former toward open circuit position in all positions of the latter, while an extension 9 of said arm is normally engaged by a pivoted latch 10 for restraining such movement thereof, subject, 50 however, to release of said latch by a tripping coil 11 upon overload. The lever 7 is pivoted medially upon a fixed supporting bracket 12 and operable for opening and closing the switch by means of a handle 13

acting through a toggle connection, all of the 55 aforementioned parts being carried in suitable operative relation upon an insulating panel 15.

The fixed contacts are secured upon the panel 15 by means of studs 16 projecting 60 therefrom, while the movable contacts are resiliently secured in insulated relation, and in a known manner, to the upper outer portions of the switch arm 5 for movement therewith, the respective pairs of contacts 65 being separated by an insulating barrier 17.

Said switch arm preferably comprises an integral sheet metal stamping including a substantially flat body portion 18, an angularly extending portion 19, and a pair of 70 spaced downwardly projecting lugs 20, one of said lugs being continued and offset to form the latch engaging extension 9.

The lever 7 also comprises an integral sheet metal stamping having a body portion 75 21 and parallel side portions 22, the upper end of said body portion being separated from said side portions and bent backwardly therefrom, and the lower ends of said side portions projecting beyond said 80 body portion as shown.

The lever 7 is pivotally mounted between a pair of arms 23 of the bracket 12 by means of a pin 24 extending therethrough and through the side portions 22 of said lever, 85 the upper ends of said side portions extending between the lugs 20 of the switch arm 5 for pivotal connection therewith by means of a pin 25. The spring 8 is secured between the bent upper end of the lever 7 and the 90 body of the arm 5 while outward movement of said arm is limited by a pair of rollers 26 carried by the lugs 20 and adapted to engage a pair of downwardly facing stop surfaces 27 on the upper portion of the 95 bracket 12.

The toggle member comprises a pair of links of which the outer link 28 is pivoted between the downwardly projecting side members 22 of the lever 7, the inner link 29 100 being pivotally mounted at 30 between extensions 31 of the bracket 12, while a fixed stop 32 serves to limit displacement of the toggle in an upward direction. A shaft 33 carrying the handle 13 is rigidly secured to 105 the link 29 for manual operation of the switch.

The latch 10 is pivotally mounted upon

the bracket 12 in such relation as normally to engage a roller 34 carried by the switch arm extension 9, said latch being provided with a laterally extending lug 35 to be engaged by a corresponding lug 36 upon a tripping lever 37 actuated by the tripping coil 11 whereupon by energization of said coil the latch is released and the switch opens in response to its bias.

10 The tripping coil 11 is supported upon the panel 15 at one side of the switch mechanism above described, with the tripping lever 37 pivoted below said coil in suitable relation for tripping the latch, and biased 15 to non-engaging position by a weight 38 or otherwise, said coil being further provided with calibrating means 39 of known construction.

In practice, the various contacts and the 20 tripping coil are provided with the usual circuit connections, and the entire mechanism is inclosed within a rectangular casing 40 secured to the panel 15 and of suitable dimensions to permit complete opening movement of the contacts 3, 4 and flexing of the 25 toggle connection, the space required by the remaining portions of the switch being within the limits thus established. The operating handle 13 is preferably located outside 30 the casing, as shown.

The switch may be operated manually by actuation of the handle 13 to flex the toggle connection downwardly, in which case the switch arm 5 and the upper portion of the 35 lever 7 move substantially as a unit about the axis 24. Upon the occurrence of an overload the tripping lever 37 moves upwardly to trip the latch 10 whereupon the switch arm 5 pivots about the axis 25 to open position under the action of the spring 8, the 40 lever 7 and other associated parts remaining stationary during such operation.

To close the switch following such opening, the operating handle 13 is first moved 45 to flex the toggle connection thereby forcing the upper end of the lever 7 outwardly against the tension of the spring 8. The switch arm 5 is prevented from following such movement of the lever 7 by the engagement 50 of the rollers 26 against the fixed stop surfaces 27 whereby said switch arm pivots about the axis 25 until the roller 34 is engaged by the latch 10. Following such preparatory movement, the switch is closed 55 by reverse movement of the operating handle, which serves to straighten the toggle connection for swinging the lower end of the lever 7 outwardly about the axis 24. The switch arm 5, being constrained by the 60 latch 10 to follow the movement of said lever, is thus swung inwardly to circuit closing position.

Should a condition of overload exist upon such closure of the switch, the coil 11 is at 65 once energized to trip the latch, whereupon

the switch arm 5 immediately moves about the axis 25 to open position in response to its bias, whereby permanent closure of the switch under such conditions is prevented.

The spring 8 being located between the 70 lever 7 and the switch arm 5 is compressed during movement of the handle 13 preparatory to closure of the switch and therefore offers no opposition to subsequent closing movement thereof. To further facilitate actuation of the switch, the roller 34 is preferably arranged to be coaxial with the pivot point 24 of the lever 7 during engagement by the latch 10 whereby the arm 5 and the lever 7 are oscillatable as a unit about said 75 common axis, although this precise arrangement of the spring and associated parts is not essential to successful operation of the switch. The stops 27 are so spaced from the rollers 26 and the other switch parts are so 80 proportioned as to insure substantially the same separation of the contacts upon overload opening as upon opening through the manually controlled means.

What I claim as new and desire to secure 90 by Letters Patent is:

1. In a circuit breaker, the combination with relatively movable contacts, of a pivoted lever, a switch arm carrying certain of said contacts, said arm being pivotally 95 mounted upon said lever for movement therewith and being biased to move relatively thereto for disengagement of said contacts, electromagnetically controlled means for restraining said switch arm against such 100 movement subject to release under abnormal electrical conditions and means for actuating said lever, said means being operable for moving said arm to position of restraint following movement thereof in response to its 105 bias and thereafter operable for moving said arm to closed circuit position during restraint of said arm by said restraining means.

2. In a circuit breaker, the combination 110 with relatively movable contacts, of a pivoted lever, a switch arm carrying certain of said contacts, said arm being pivotally mounted upon said lever for movement therewith and being biased to move relatively thereto for disengagement of said contacts, an electromagnetically controlled latch pivoted at a fixed point and adapted to restrain said arm against such movement 115 subject to release under abnormal electrical conditions and means for actuating said lever, said means being operable for moving said arm to position of restraint following movement thereof in response to its bias and thereafter operable for moving said arm to 120 closed circuit position during restraint of said arm by said latch.

3. In a circuit breaker, in combination, a pivotally mounted lever, a switch arm mounted thereon for joint movement there- 125 130

with and movement relative thereto, a latch member pivoted at a fixed point and effective to restrain said arm against such movement, electro-responsive means for tripping said latch and maintaining the same ineffective during overloads, and actuating means operable to move said lever and said arm jointly in either direction during restraint of the latter by said latch.

10 4. In a circuit breaker, in combination, a pivotally mounted lever, a switch arm mounted thereon for joint movement therewith and movement relative thereto, a latch member pivoted at a fixed point and adapted to engage an extension of said arm for restraining the same against such independent movement, electro-responsive means for rendering said member ineffective during overloads, and actuating means for said lever operable upon release of said arm by said latch to restore the former to position suitable for engagement by the latter.

5. In a circuit breaker, in combination, a pivotally mounted lever, a switch arm mounted thereon for joint movement therewith and movement relative thereto, a latch member pivoted at a fixed point and adapted to engage an extension of said arm for restraining the same against such independent movement, electro-responsive means for rendering said member ineffective during overloads, and actuating means for said lever operable upon release of said arm by said latch to restore the former to position suitable for engagement by the latter and during such engagement to move said lever and said arm jointly in either direction.

6. In a circuit breaker, in combination, a pivotally mounted lever, a switch arm mounted thereon and movable therewith to closed circuit position said arm being movable independently of said lever to open circuit position, a latch pivoted at a fixed point for restraining said arm against said latter movement and electro-responsive

means for tripping said latch upon over-load.

7. In a circuit breaker, in combination, a fixed support, a lever pivoted medially thereon, a switch arm pivotally mounted upon said lever and biased to move relatively thereto to open circuit position, said support and said arm having co-operating parts for limiting such movement, means for normally restraining said arm against such movement, operating means for moving said lever and said arm jointly to closed circuit position during restraint of the former by said restraining means, and electro-responsive means effective upon overload to release said arm from said restraining means for movement of said arm to open circuit position and for rendering said operating means ineffective to move said arm to closed circuit position prior to reengagement of said restraining means.

8. In a circuit breaker, in combination, a fixed support, a lever pivoted medially thereon, a switch arm pivotally mounted upon said lever and biased to move relatively thereto to open circuit position, a roller carried by said arm and adapted to engage a stop carried by said support for limiting such movement, a latch member pivoted upon said support for normally restraining said arm against such movement, operating means for moving said arm and said lever jointly to circuit closing or circuit opening position during restraint of said arm by said latch, said operating means including a toggle connection adapted to co-operate with a portion of said support for normally retaining said lever in closed circuit position, and electro-responsive means effective upon overload to trip said latch member for movement of said switch arm to open circuit position in response to its bias.

In witness whereof, I have hereunto subscribed my name.

CLARENCE T. EVANS.
